UNITED STATES PATENT OFFICE.

HUGO JUNKERS, OF DESSAU, GERMANY.

FUEL CONTROL IN INTERNAL-COMBUSTION ENGINES.

Application filed November 17, 1921, Serial No. 515,987, and in Germany June 1, 1921.

My invention relates to internal combustion engines and more especially to the delivery of fuel in such engines.

In internal combustion engines in which liquid fuel is injected into a strongly compressed charge of air near the inner dead center and ignited by the heat of compression, it is known to inject the fuel positively, that is, without the aid of atomizing air.

If it be desired to dispense with a separate controlled injection valve at the point of injection in the working cylinder of such engine, the beginning and the end of the injection period must be determined exclusively by the fuel pump. By dispensing with such control valve, the design of the engine is greatly simplified and moreover the dangers are obviated which are caused by the sticking of the valve, viz. excessive and inadmissible increase of pressure in the working cylinder in consequence of too early injection of fuel.

My invention relates to a method of so controlling the fuel pump that the process of injection is controlled exclusively by the fuel pump. To this end, I so control the pump that the beginning of delivery in relation to the crank circle or the stroke of the working piston is approximately constant for all loads while the end of the delivery is determined by the operation of an adjustable actuating member of the pump or its control. As compared to the injection by compressed air, the advantage is hereby achieved that the injection is positively effected at all numbers of revolutions within a predetermined angular movement of the crank, so that a perfect control of the process of combustion is possible under all conditions of operation and no dangerous increase of pressure at low speed can occur.

My invention may be carried out in various ways. I prefer varying the quantity delivered or, in other words, the charge by aid of a cam whose angular position can be adjusted. It may be turned concentrically to its shaft, but, in this case, special means are required for fixing the constant beginning of delivery, such as, for instance, a separate control of the suction valve or a separate auxiliary cam whose motion determines the beginning of the delivery stroke proper. However, the cam for actuating the pump may also be so arranged as to be adjusted about a point eccentric to the axis of the

shaft, the constant beginning of delivery being determined by giving the contour of the lifting surface of the cam the form of part of a circle surrounding this centre. I further prefer provided means by which the pump piston is rapidly withdrawn for a short distance immediately after having attained the end of its delivery stroke, for example by an abruptly descending surface on the cam immediately following its highest point, or by means of equivalent means in the system, of controlling levers. In this way an afterdripping of the nozzle, after injection has been effected, is avoided.

In the drawings affixed to this specification and forming part thereof, several embodiments of my invention are illustrated diagrammatically by way of example. In the drawings

Fig. 1 is a partial longitudinal section of the working cylinder, the fuel pump and the actuating gear.

Fig. 2 is a like view of a modified form,

Fig. 3 is a similar view of a fuel pump and an adjustable cam having an eccentric pivot,

Fig. 4 is a section of a modified form of such a cam.

Referring to Fig. 1, the piston 1 of the pump is actuated by a cam 3 adapted to be adjusted circumferentially on a shaft 2 in such a manner that the stroke of piston 1 will be constant, these strokes, however, beginning and ending at various points of the crank circle according to the positions of the cam. The cam may be adjusted by hand or by aid of a governor. The beginning of the delivery is determined by the closing of the suction valve 4 of the pump, while its end is determined by the end of the piston stroke. In order to always close the valve 4 at the same point of the crank circle, it is positively controlled in dependency upon the working of the engine, in the present case by means of an eccentric 6 fixed on shaft 2, which by aid of rods 7 and 8 and a double armed lever 9 operates a cam slide 10 to lift the valve 4 in the usual manner. The suction valve 4 is acted upon by a pressure spring 4^a and opens outwards, thus also forming a safety valve for the pump.

This arrangement may be modified by causing the governor to adjust not the cam 3 but the eccentric 6. In this case the pump with its uniform motion will determine the constant beginning and the variable moment

of opening of valve 4 will determine the end of the delivery stroke. The valve 4 may then be kept open so long that it not only operates as a non-return valve in the sense referred to, but also as a suction valve for the pump. I may, however, provide a special suction device, either a valve or a suction port.

In the modification illustrated in Fig. 2, 10 the beginning and the end of the delivery are determined by two cams 11 and 12, which both act on the pump piston 1, thus rendering controlled valves at the pump superfluous. Cams 11 and 12 are located on parallel 15 shafts 15 and 16 which are coupled by gears 13 and 14. The shafts revolve with equal speed but in opposite directions as indicated by the arrows. The cams cooperate with rollers 17 and 18 which are connected with 20 one another and with the piston 1 by means of a balance lever 19. Cam 11 is fixed on shaft 15, whereas cam 12 may be adjusted as circumferentially with regard to shaft 16 or gear 14 by hand or by aid of a governor. 25 This pump operates as follows: first, the roller 18 is lifted by cam 12, so that the piston 1 is raised to near the inlet port 20 which it controls. During this stroke of the piston 30 no fuel is as yet delivered. When the lifting surface of cam 11 engages roller 17, the piston 1 is raised further, so as to close port 20. At this moment the delivery begins and is continued until the roller 18 passes the rear surface of cam 12 and piston 1 returns 35 in order to start for the suction stroke. As the cams revolve further, the roller 17 also passes over the rear face of cam 11. In this period the piston 1 performs an ineffective stroke. Owing to the cam 11 being rigidly 40 fixed on shaft 15 the inlet port 20 is closed and delivery begins always at the same position of the crank of the working piston. The length of the effective pump piston stroke depends upon whether, while roller 45 17 is being lifted by cam 11, roller 18 still runs on the base circle of cam 12 or is already about to pass over the rear face of the cam. While in the former case the maximum quantity is delivered, it is small 50 in the latter case and nil when roller 18 has already reached the base circle of cam 12, while roller 17 is being lifted by cam 11.

Further simplification is effected according to Fig. 3, by disposing the pivot 21, of 55 cam 22 eccentrically to the axis 23 of the cam shaft. In this case the delivery of the pump may be adjusted by means of a single cam without providing separate means for maintaining the beginning of delivery constant. This is achieved in a simple manner 60 by forming the lifting surface 24 of the cam according to a circle drawn around its pivot 21. The lifting surface of cam 22 then intersects the main cam 25 in the same point 26 65 at all positions of cam 22, so that the piston

1 is lifted always at the same position of the crank.

In order that the roller may pass from cam 25 to cam 22 free of shocks, the main cam 25 is formed so as to extend tangentially to surface 24 at 26. According to the position of cam 22, its radial projection beyond the main cam 25 and with it the pump stroke vary. Immediately adjoining the highest point of face 24, there extends an abrupt portion 27, of the rear surface which effects a rapid backward movement of the pump piston immediately after it has performed its delivery stroke. This prevents drops of fuel from emerging from the nozzle 80 after the injection.

The device illustrated in Fig. 3 is further improved by forming the cam 22 as a closed ring surrounding the shaft 31 as illustrated in Fig. 4. This cam has a lifting surface 85 24, concentric with its pivot 21 and a base circle 32 replacing the base circle 25 in Fig. 13. On the shaft 31 is fixed a spider 33 carrying a pair of centrifugal masses 34 acted upon by springs 35 and coupled by means 90 of rods 36, 37 pivoted to the lever 38 which is connected with the cam 32 whereby, when the position of the masses 34 is changed, the cam will rock about the pivot 21. Owing to the approximately circular form of the surface 32 no undue accelerations and no excessive ineffective strokes will occur.

The cams are preferably adjusted in all cases by means of a shaft governor on the cam shaft. Instead of cams eccentric or 100 cranks may be provided, which are connected with the governor in a manner similar to that of adjustable cam disks and eccentricities.

The means disclosed in Figs. 2 to 4 for actuating the pump piston may also be used 105 for actuating a valve such as 4 in Fig. 1. In this case the pump piston will be imparted a permanently constant stroke by means of an unvariable actuating member and the entire control of the pump including the beginning and the end of delivery, is determined exclusively by the closing and opening of the valve. This arrangement 110 renders necessary one actuating part more than the others, but it involves the advantage that the cam surfaces which owing to the high fuel pressure are subject to heavy wear, are combined at the valve and can easily be exchanged.

I claim:

1. Means for regulating the delivery of fuel in internal combustion engines comprising a fuel pump cylinder and piston, controlling means in said pump for causing the end of the effective strokes to coincide with the end of the pump stroke, an engine crank shaft, a rotating member driven by said crank shaft for driving said pump piston and shiftable in its plane of movement, a regulating device, means connecting said 120

- member and regulating device for shifting said member in the plane of its movement so as to drive said pump piston with strokes of varying ends with regard to the engine 5 crank circle, and means for keeping the commencement of delivery of said pump constant with respect to the engine crank circle.
2. In a device of the kind described in combination, a fuel pump cylinder and piston 10 ton, an engine crank shaft, a controlled admission means connected with said cylinder, means for closing said admission means always at the same point of the crank circle and means for moving said piston adapted 15 to be adjusted so as to shift the end of the delivery stroke of said piston.
3. In a device of the kind described in combination, a fuel pump cylinder and piston, an engine crank shaft and a cam capable 20 of adjustment in its plane of rotation for varying the effective stroke of said piston while causing the delivery of the fuel to always begin at the same point of the crank circle.
- 25 4. In a device of the kind described in combination, a fuel pump cylinder and piston, an engine crank shaft, a controlled admission means connected with said cylinder, means for closing said admission means 30 always at the same point of the crank circle and a cam capable of adjustment in its plane of rotation for moving said piston.
5. In a device of the kind described in combination, a fuel pump cylinder and piston, an engine crank shaft, a cam capable of 35 adjustment in its plane of rotation for varying the effective stroke of said piston while causing the delivery of the fuel to always begin at the same point of the crank circle, and a governor for adjusting said cam.
- 40 6. In a device of the kind described in combination, a fuel pump cylinder and piston, an engine crank shaft, a controlled admission means connected with said cylinder, means for closing said admission means always at the same point of the crank circle, a cam capable of adjustment in its plane of rotation for moving said piston and a governor for adjusting said cam.
7. In a device of the kind described in combination, a fuel pump cylinder and piston, an engine crank shaft and means for varying the effective stroke of said piston while causing the delivery of the fuel to always begin at the same point of the crank circle, said means comprising a cam adapted 55 to turn about an eccentric pivot and whose lifting surface has the form of part of a circle concentric to said pivot.
8. In a device of the kind described in combination, a fuel pump cylinder and piston, an engine crank shaft and means for varying the effective stroke of said piston while causing the delivery of the fuel to always begin at the same point of the crank circle, said means comprising a cam shaft 60 and an annular cam surrounding said shaft and adapted to turn about an eccentric pivot outside said shaft, the lifting surface of said cam having the form of part of a circle concentric to said pivot.
9. In a device of the kind described in combination, a fuel pump cylinder and piston, an engine crank shaft, means for varying the effective stroke of said piston while 65 causing the delivery of the fuel to always begin at the same point of the crank circle and means for a quick return of said pump piston at the end of its delivery stroke.

In testimony whereof I affix my signature.

HUGO JUNKERS.
